United States Patent Office

Des. 181,841
Patented Jan. 7, 1958

181,841

WRITING INSTRUMENT

Don Doman, Janesville, Wis., assignor to The Parker Pen Company, Janesville, Wis., a corporation of Wisconsin

Application May 18, 1955, Serial No. 36,074

Term of patent 14 years

(Cl. D74—17)

The figure on the drawing is a side elevational view of a writing instrument showing my new design. The writing instrument disclosed is circular in cross section throughout.

I claim:

The ornamental design for a writing instrument, substantially as shown and described.
